UNITED STATES PATENT OFFICE.

JAMES C. SERGESON, OF PHILADELPHIA, PENNSYLVANIA.

LOOM-SHUTTLE.

1,278,034.

Specification of Letters Patent. Patented Sept. 3, 1918.

Application filed February 6, 1918. Serial No. 215,585.

To all whom it may concern:

Be it known that I, JAMES C. SERGESON, a citizen of the United States, residing in the city and county of Philadelphia, State 5 of Pennsylvania, have invented a new and useful Loom-Shuttle, of which the following is a specification.

My invention consists of a loom shuttle having the guarding bar for the bobbin provided with novel means for retaining the bobbin in position in a firm, convenient, 10 practical and inexpensive manner.

It also consists in constructing said means as an integral continuity of said bar.

15 It consists also in providing the shuttle with novel means for locking said bar in position.

It consists also of a device on said guarding bar for running the yarn or thread true 20 to the threading passage in the nose of the shuttle.

The invention is satisfactorily illustrated in the accompanying drawings, but the important instrumentalities thereof may be 25 varied, and so it is to be understood that the invention is not limited to the specific details shown and described, as long as they are within the spirit or scope of the claims.

Figure 1 represents a plan view of a 30 shuttle embodying my invention.

Figs. 2 and 3 represent longitudinal sections respectively of opposite end portions of the shuttle on an enlarged scale.

Fig. 4 represents a transverse section on 35 line 4—4 Fig. 3.

Fig. 5 represents a longitudinal section of a portion on line 5—5 Fig. 4.

Fig. 6 represents a transverse section of a portion on line 6—6 Fig. 3.

40 Similar numerals of reference indicate corresponding parts in the figures.

Referring to the drawings—

1 designates the body of the shuttle, and 45 2 designates the bobbin therein said bobbin being mounted on the rod or spindle 3, as usual.

The base of the bobbin has a portion cut away as at 4, and has in its side adjacent to said portion the transversely-extending groove 50 or recess 5. 6 designates a plate which is mounted by the rod 7 as an axis on the body adjacent to the base of the bobbin, it being formed of metal preferably steel, and is adapted to extend over the bobbin with the 55 yarn or thread thereon as a cover and

guard therefor, and also to retain the bobbin properly in the body of the shuttle, said plate being somewhat bowed and resilient in its nature so as to be held firmly in position when it is closed, and to spring 60 out therefrom when released, as will be hereinafter again referred to.

In order to retain the bobbin in position, the plate 6 is formed at its axial end with the tongue 8 which is an integral portion of 65 the plate 6, it being noticed that said plate is continued toward its axial end where it is formed with the sleeve 9 in which is received the axial rod 7, and then bent back on itself as at 10 which is adapted to be pressed 70 inwardly by the contiguous portion 11 of the plate, the terminal of said bent back portion 10 opposite to the sleeve 9 having thereon the inturned tongue 8 which extends at an angle from said terminal and is adapted 75 when the plate is lowered to enter the recess 5 in the base of the bobbin, thus causing the bobbin to be interlocked by said tongue, and consequently by the plate 6, whereby it is held in position in the body of the shuttle 80 in a firm, simple and efficient manner, it being seen that when the plate is raised said tongue emerges from the recess 5, and so the bobbin is unlocked and may be removed from the body of the shuttle. 85

In order to lock the plate 6 when in closed position, the terminal thereof opposite to the sleeve 9 has thereon the outturned lip 12 which is adapted to be engaged by the hook-like members 13 on the latch 14 which 90 is axially mounted on its inner end on the rod 15 which latter is secured in the body 1 adjacent to the threading passage 16 in the nose of the body of the shuttle, said latch having therein in the direction of its length 95 the slot 17 through which the yarn or thread runs from the bobbin to said passage, said slot being open at the top or the free end of the latch, whereby when the yarn or thread is presented to said slot it may be pressed down thereinto so as to enter the same when it is guided to said threading passage 16 and so entered in the latter.

In order to hold the latch engaged with the lip 12 it is engaged by one end of the 105 coil spring 18 and so pressed against said lip, the other end of said spring being held in the adjacent portion of the body, it being guided and retained in place by the stud 19 which is secured to the latch and enters 110

the adjacent end of the spring, as most plainly shown in Fig. 5.

When the plate is pressed into the body the lip is removed from the hook-like members 13. Then the latch is pushed back when said lip is cleared of said members, and said plate may spring out and so uncover the bobbin.

On the inner side of the plate 6 and firmly secured thereto is the leg 20 which enters the body of the shuttle adjacent to the latch 14 and head end of the bobbin it being of open form, staple-like or U-shape, as an open eye preferably of elongated form through which the yarn or thread passes freely from the bobbin to the slot 17 in the latch 14, and so centering the yarn or thread true to said slot and consequently to the threading passage, thus effectively preventing what is known as ballooning of the yarn or thread.

It will be noticed, referring more particularly to Fig. 4, that the slot or passage 17 in the latch 14 is narrow in width sufficient to permit in weaving the yarn or thread to run freely therethrough from the leg or eye 20, but should there be a knot in the yarn or thread, it will be caught or trapped on the walls of said slot so that the yarn or thread in its draft will break between said walls and the threading passage retaining the knot within the shuttle and preventing it from being woven.

Having thus described my invention what I claim as new and desire to secure by Letters Patent, is:—

1. In a shuttle, a guard and a retainer for a bobbin composed of a plate, a sleeve on the latter by which said plate is mounted on the body of the shuttle, said plate having a portion of itself bent back on the plate from the axis of the latter, and a tongue on the terminal of said portion, said tongue being

adapted to engage the bobbin to interlock the same in the shuttle.

45

2. A shuttle having a guard for the bobbin and a retainer therefor in the body of the shuttle composed of a plate adapted to be pivotally mounted on said body, a tongue member on said plate near the pivotal end thereof, and a bobbin having therein a transversely extended groove in which said tongue member is adapted to be seated.

3. In a shuttle, a guard and a retainer for a bobbin in the shuttle composed of a swinging plate, a lip on the free end of the latter, and a latch on the body of the shuttle having a hook-like member adapted to engage said lip, said latch having therein a longitudinally extending slot which is open at its free end and adapted to be in communication with the threading passage in the body of the shuttle.

4. In a shuttle, a guard and a retainer for the bobbin comprising a pivoted plate, and a tongue member thereon disposed beneath the body portion of said plate near the pivotal end thereof and extending from the under face of the plate with its free end engageable in a recess in the side of the bobbin and engageable therewith.

5. In a shuttle, a retainer for a bobbin composed of a latch-like plate mounted at one end of the body of the shuttle, a latch-like device mounted on the opposite end of said body adjacent to the threading passage of the latter, said plate having therein a longitudinally extending slot which is open at the free end of the plate and adapted to be in communication with said threading passage.

JAMES C. SERGESON.
